United States Patent Office

Des. 232,717
Patented Sept. 10, 1974

232,717

WHEEL

Elliott M. Morris, Corona Del Mar, Calif., assignor to
Morris Industries, Santa Ana, Calif.

Filed July 17, 1972, Ser. No. 272,310

Term of patent 14 years

Int. Cl. D12—16
U.S. Cl. D12—205

FIG. 1

FIG. 2

FIG. 3

FIG. 4

FIG. 1 is a top plan view of a wheel showing the invention;

FIG. 2 is a side view of FIG. 1; and

FIG. 3 and 4 are half-views of axial cross section taken at lines 3—3 and 4—4, respectively, and these recur each 51½° around the central axis.

I claim:

The ornamental design for a wheel, as shown.
